CONSECUTIVE NUMERAL PUNCHING
MECHANISM

Alexander G. Duff, Toronto, Ontario, Canada, assignor to Remington Rand Inc., New York, N. Y., a corporation of Delaware

Application May 24, 1950, Serial No. 163,853

3 Claims. (Cl. 164—111)

1

This invention relates to card punching machines, and in particular to one in which cards may be successively punched to provide data designation perforations.

In cards used to control the operation of business machines the data is in the nature of one or more holes arranged in code combination at various data designation positions in the columns of the card. In order to punch the holes in the proper locations the operation of code bars has been controlled by a tabulator from which total designations are transferred to a punching mechanism, as shown in the patents to W. Kuhlman et al., 1,998,281, granted April 16, 1935, and to A. G. Rindfleisch, 2,354,549, granted July 25, 1944. In these machines the punch setting mechanism has been a part of the machine from which the totals are to be transferred and the setting mechanism has been actuated solely by the machine of which it forms a part. In the printing of checks, for example, it may be desirable to punch in each card, code designations representing a serial number, and to punch in each succeeding card the next number of a series, so that when the checks are printed they will bear progressively arranged identifying numbers.

It is an object of the invention, therefore, to embody in a punch, a mechanism for automatically varying the operation of the punch controlling code bars, so that set up of the punch means will produce perforations in consecutively fed cards that will control the subsequent printing of progressive numbers.

A still further object of the invention is to provide a mechanism that is an integral part of the punch structure, that will operate on each successive cycle to bring about sequential punchings in one or more fields of a card and one which can be set to start a series of numbers in any ordinal group desired.

Another object of the invention is to provide a manually settable punch controlling means which will serve as an indicator to show at what number in the series the punch is operating, the capacity of the control means being only limited to the space on the card reserved for the punched identification data.

Other objects of the invention will be apparent in the course of the following description and claims which disclose, by way of example the principle of the invention, and a preferred means for carrying it out as further illustrated in the accompanying drawing, in which

Figs. 1 and 2 combined show the essential ele-

2

ments of a punch, in side elevation, including the means for controlling the operation thereof in accordance with the invention;

Fig. 3 is a fragmentary isometric view of the 5 carry mechanism with parts thereof being broken away to show the structure;

Fig. 4 is a view in front elevation of the setting mechanism showing the relative location of the selector disks and controls therefor; and

10 Fig. 5 is a fragmentary isometric view of the setting dials that indicate the consecutive punchings of the cards.

The punch mechanisms disclosed in the Patents 1,998,281 and 2,354,549 above referred to, find counterparts of their structures in the present application which will be briefly reviewed herein, it being understood that complete disclosures of the machine operating parts are to be found in the patents referred to, and may be so employed in the present embodiment of the invention.

Referring to the drawings in detail, 100 indicates a card magazine mounted in a lower base or frame section 110 of the machine with its associated parts which include punches 101, a card pocket 102, rows of set bars 103 which are depressed, in accordance with data to be punched and are so held by locking slides 104. The set bars 103 hold blocking pins 105 depressed so that when a card is raised, the punches 101 prevented from rising by certain pins 105, perforate the card.

Cards are fed singly from the magazine 100 by a picker knife 106 actuated by a cam 107 on drive shaft 108. The card is carried by feed rolls 111 to a punch chamber or basket 114 where it is held by a card stop 112 until it is punched, after which it is ejected and carried by eject rolls 113 to said card pocket 102. The drive of the parts, including the shaft 108, is shown in the Patent 2,354,549, and during the period that the card is held by the stop 112 the basket 114 is raised by the cam 109 and the card is punched in accordance with the settings of the bars 103 and pins 105.

45 The lower frame 110 that supports the punch mechanism is surmounted by an upper frame 115 in which is journaled a cam shaft 116 for actuating the set up mechanism and the numbering or selecting mechanism to be described. Shaft 116 is driven from the drive shaft 108 by any suitable means such as a chain (162 of Fig. 1 in Patent 2,354,549). The selecting mechanism includes sensing slide bars 118 extending through 50 the frame and guided between rollers 117 at one

end and passing under a cross bar of the machine frame at the opposite end. One bar 118 is provided for each denominational order of numerals to be punched and each bar carries a contact collar 119 which is yieldably maintained against the edge of a cross head 134 by a spring 136 connecting said cross head with a block 121 fixed to each bar 118. Each block has an arm whose roller 122 rides horizontally in a vertically reciprocating head 123 to position a code bar or plate 124, depending from the block 121, to overlie the upper ends of wires 120 that are to be depressed to "set" the pins 105 in accordance with a longitudinal movement of the slide bar 118. The spring 136 causes each bar to follow the movement of the cross head until the end of the bar contacts the stepped peripheral edge of a disk 142 after which the cross head continues its stroke, as permitted by the spring 136.

The vertical reciprocation of the head 123 is caused by the movement of a gear 132 along a rack 133 fixed in the upper frame 115 when a shaft 128, journaled in the head 123 and to which the gear 132 is secured, is rocked through an arm 130 and a link 131. Movement is imparted to link 131 by a bell-crank 127 controlled from a cam 126 fast on shaft 116. A cam 125 operates a bell-crank 135 which reciprocates the cross head 134 once in each machine cycle.

The bottom edge of each interponent code bar 124 has its projection adapted to coact with the upper ends of different wires 120, so that the code perforations for each numeral can be punched, the wires 120 including suitable Y-wire branches, as commonly used in machines in the punched card art, for punching the same numeral code holes in different fields of the same card, if desired. The amount of movement of the code bar 124 depends upon which of the sector faces 143 of the disk 142 is engaged by the bar 118. One disk 142 is provided for each bar 118, the disks being mounted on a shaft 141 extending between the side walls of an auxiliary frame 140 secured to frame 115. Each disk has a spiral shaped periphery divided into ten sector faces 143 spaced a different radial distance from the center of shaft 141 so that the bars 118 can be successively moved to position the code bars in proper increments to punch code holes representing successive numerals of each denominational order.

The means for rotating the disks 142 to successively position the respective sector faces 143 in alignment with the ends of the bars 118 includes a spur gear 144 fixed to each disk and meshing with an idler gear 145 mounted on shaft 146 for rotation by the drive gear 147 of an accumulator mechanism. The latter includes a shaft 148 mounted in frame 140 on which, for each disk 142, is rotatably mounted a drive gear 147 having a ratchet wheel 150 fixed to one side thereof and a carry disk 162 secured to the opposite side thereof. Each disk 162 has a single pawl notch corresponding with one tooth of a ratchet wheel 150. As many of these groups, each including a gear 147, a ratchet 150 and a carry disk 162, may be used as necessary for the number of orders to be punched in the card. Each gear 147 through the gears 145 and 144 controls the operation of a sector disk 142. Reference is made to Fig. 3 wherein the ratchet wheel 150 nearest to the observer, with its gear 147 and disk 162, will be considered the units group, and is operated through a pawl 151 pivoted on an arm 163 fixed to a rock shaft 149 and held in engagement with the ratchet wheel 150 by a spring 153.

While the pawl 151 of the near ratchet engages the teeth of the latter alone, it will be observed that the pawls for the succeeding higher orders ride on the peripheries of the disks 162 and are dimensioned to overlie the peripheries of the ratchets 150 so that "carry" is effected each time the pawl drops into the notch of the disk 162 to engage a tooth of the adjacent ratchet 150 of the next higher order. The shaft 149 is rocked once in each machine cycle, by the depending lever end 152 of one of the pawls 151, through a link having parts 154 and 155 joined by a suitable pin-in-a-slot connection. The latter is rendered operative by the use of a spring pressed pin 168 for securing the parts relatively fixed so that endwise movement of the link rocks the shaft 149 each time that a bellcrank 158 pivoted on shaft 159 and carrying a roller 160 is oscillated by a cam 161, fast on the shaft 148. When the pin 168 is withdrawn the part 155 has free movement and does not move part 154. The position of each gear 147 is yieldably maintained by a roller or pin 156 in a spring urged lever 157.

Each of the gears 145 meshes with a counter gear 165 mounted for free rotation on a shaft 166 and fixed to a dial 167 the periphery of which is laterally fluted between numeral indices to provide for manual operation of the mechanism either to set it to "zero" or starting position or to set the number at which the punching is to begin. The dials extend through an opening in a plate conveniently located at the open end of the frame 140, and as they operate with each motion of the gears 145 they serve as a visual count indicator of any series of numbers being punched in the cards.

In the operation of the machine, assuming that the first card is to be punched to correspond with the numeral 1 and subsequent cards with numerals 2, 3, etc., one cycle of shaft 116 will cause the cam 161 to rotate the units order sector disk 142 through 36° to align the second or numeral '1 sector with the slide bar 118 controlled by said units order disk. In properly timed relation, the cross head 134 and the reciprocating head 123 operate under the influence of their respective control cams to coordinate set the code bar 124 and depress the same to set the pins 105 so that a rise of the card chamber 114 will cause the code holes representing a numeral 1 to be punched in the proper column of the card field allotted to serial numbering. In succeeding cycles of the machine operation, the continued actuation of the pawls 151, through the linkage described, will intermittently rotate the sector disks 142 to automatically cause the perforations, representing successive numerals, to be punched in the card. The disks 162 "carry" the operation of the sector disks from the units order through the successive orders until the numeral punching is completed. Inspection of the counting dials 167 will reveal the progress of the punchings at any stage during the operation of the machine. The dials are also used for resetting the disks and associated parts to zero position, by manual operation thereof to their zero positions. Through the use of the dials, it is evident that numbering can begin with any selected number by simply setting the dials, so that the first number of the series will be punched on the first cycle of the machine, and numbers in rotation thereafter will be set up and punched automatically until the punchings are completed.

While I have described what I consider to be a highly desirable embodiment of my invention,

it is obvious that many changes in form could be made without departing from the spirit of my invention, and I, therefore, do not limit myself to the exact form herein shown and described, nor to anything less than the whole of my invention as hereinbefore set forth, and as hereinafter claimed.

What I claim as new, and desire to secure by Letters Patent, is:

1. In a punched card numbering machine, a punch mechanism, means for controlling said punch mechanism to perforate cards seriatim in a code representative of consecutive numbers, comprising a plurality of spiral sectors, a spur gear attached to each spiral sector, an idler gear for each of said sector gears, a driving gear for each of said idler gears, differential means for actuating said driving gears, means actuatable by said punch mechanism for actuating said differential means, and manually operable means for selectively pre-positioning said spiral sectors.

2. In a punched card numbering machine, a punch mechanism, means for controlling said punch mechanism to perforate cards seriatim in a code representative of consecutive numbers, comprising a plurality of spiral sectors, a spur gear attached to each spiral sector, an idler gear for each of said spur gears engaging the associated spur gear, a driving gear for each of said

5 idler gears engaging the associated idler gear, pawl and ratchet means for rotating said driving gears, means for actuating said pawl and ratchet means once during each cycle of operation of said punch mechanism, and means for disabling said pawl and ratchet actuating means.

10 3. A machine for punching cards with holes representative of consecutive numbers including punches, set bars overlying said punches, code plates, means for moving said code plates to actuate said set bars, slide bars, spiral sectors with which said slide bars coact to differentially set the code plates relatively to the set bars, drive means including a carry mechanism and gear means for actuating said sectors, a connection from said drive means to said code plate moving means, means operated by said gear means for indicating the number of cards punched, and said indicating means being manually operable to control the setting of said sectors through said gear means.

ALEXANDER G. DUFF.
